(57) **CLAIM**

The ornamental design for packing box lining partition, as shown and described.

DESCRIPTION

FIG. 1 is a front, top, right, perspective view of a packing box lining partition showing my new design;

FIG. 2 is a rear, bottom, left, perspective view thereof;

FIG. 3 is a rear, top, right, perspective view thereof;

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof; and,

FIG. 10 is an expanded plan view thereof.

The broken lines are shown for the purpose of illustrating fold lines that form no part of the claimed design.

1 Claim, 10 Drawing Sheets
